CLAIM

The ornamental design for a riser for trophies, or the like, as shown and described.

DESCRIPTION

FIG. 1 is a front elevational view of a riser for trophies, or the like showing my new design, the base and figure shown in broken lines for illustrative purpose only;

FIG. 2 is a rear elevational view thereof;

FIG. 3 is a top plan view thereof;

FIG. 4 is a bottom plan view thereof;

FIG. 5 is a side elevational view thereof, the opposite side being identical; and

FIG. 6 is an enlarged perspective view thereof.
